UNITED STATES PATENT OFFICE.

PERRY J. GARRISON, OF OXFORD, MICHIGAN, ASSIGNOR OF ONE-HALF TO WILLIAM REED, OF OXFORD, MICHIGAN.

DRIVING MECHANISM FOR MOTOR-VEHICLES.

1,318,373.

Specification of Letters Patent. Patented Oct. 14, 1919.

Application filed January 8, 1919. Serial No. 270,128.

To all whom it may concern:

Be it known that I, PERRY J. GARRISON, citizen of the United States, residing at Oxford, county of Oakland, State of Michigan, have invented a certain new and useful Improvement in Driving Mechanism for Motor-Vehicles, and declare the following to be a full, clear, and exact description of the same, such as will enable others skilled in the art to which it pertains to make and use the same, reference being had to the accompanying drawings, which form a part of this specification.

My invention relates to a driving mechanism for motor vehicles:—its object being to provide a simple and inexpensive power transmission between the driving shaft of a motor and the driving wheels of the vehicle which shall be efficient, not liable to get out of order, easy to install and quiet in action.

With the foregoing and other objects in view which will appear as the description proceeds, the invention resides in the combination and arrangement of parts and in the details of construction hereinafter described and claimed, it being understood that changes may be made in the precise embodiment herein disclosed without departing from the spirit of the invention.

In the accompanying drawings:—

Figure 1 is a plan view of the device with the cover plate removed, showing fragments of the axle and also of the clutch lever.

Fig. 2 is a vertical cross sectional view of the same.

Fig. 3 is a vertical sectional view on line 3—3 of Fig. 2.

Fig. 4 is an elevation of the inclosing case, showing the driving shaft in cross section and fragments of the clutch and reverse levers.

In the device shown no so called "differential mechanism" is shown but a suitable differential mechanism may be employed if desired, this feature, however, forms no part of the present invention.

Referring now to the letters of reference placed upon the drawings:—

A, denotes a chambered casing into which extends the ends of a divided rear axle B. 50 Journalized at an angle in the walls of the casing, is a rotatable disk C, provided with a plurality of apertures C¹,—arranged in concentric circles to receive the teeth of certain driving and driven pinions hereafter more 55 specifically described.

D and D¹ are pinions, mounted upon the ends of the divided axle, the teeth of which enter the apertures C¹, of one of the concentric rings of apertures, but respectively on 60 opposite sides of the disk.

E, E¹ indicate anti-friction rollers, journalized in the walls of the casing, bearing upon each side of the disk C, at a point opposite that in which the teeth of the pinions D, D¹ 65 enter the apertures of the disk.

G, denotes a hollow driving shaft actuated in the usual manner by a prime mover (not shown).

H, is a pinion loosely mounted upon said 70 shaft, the teeth of which enter one of the circular rows of apertures C¹ in the disk C.

I, indicates a pinion also loosely mounted upon the shaft, spaced from the pinion H;—the teeth of which enter a concentric row 75 of apertures in the disk to drive the latter at a different speed ratio.

J, denotes a clutch member extending transversely through a slot in the shaft G, between the pinions H and I, adapted to 80 alternately clutch the respective pinions to the driving shaft through the manual operation of a lever K, in turn operably connected with the member J, by a rod L, extending through the shaft G. 85

M, is a sprocket gear on the shaft G, connected by a driving chain N, with a sprocket gear O, on the hollow stub shaft P, journalized in the wall of the casing A.

Q, is a pinion loosely mounted upon the 90 shaft P, the teeth of which enter one of the circular rows of apertures in the disk.

C, on the underside of the latter to drive the disk in a reverse direction.

S, indicates a clutch member extending transversely through a slot in the shaft P, 5 adapted to clutch the pinion Q, to said shaft through the manual operation of the lever T, which is in turn connected to the clutch member S, by a rod U, extending through the shaft P.

10 Having indicated the several parts by reference letters, the construction and operation of the driving mechanism will be readily understood.

To operate traction or driving wheels (not 15 shown) carried by the divided axle in a forward direction, the lever K, is manually operated to shift the clutch member J, from its neutral position (shown in Fig. 3) so as to "clutch" either the pinion H, or I, 20 to the shaft G, in accordance with the speed required. The disk C, is thus actuated and the pinions D and D¹, mounted upon the inner ends of the divided axle, are thereby operated, rotating the rear axle with its traction 25 wheels in a forward direction. When it is desired to reverse the direction taken by the vehicle, the clutch member J, is thrown into a "neutral" position, by the operation of the lever K; the clutch lever T, is then 30 operated to shift the clutch member S, into engagement with the pinion Q, thereby locking it to the shaft P. Power having now been applied to the shaft P through the driving chain connection N, with the shaft 35 G,—the disk C is rotated in a reverse direction, thereby reversing the rotation of the rear axle and the traction wheels mounted thereon.

It will be seen that by the use of this 40 invention there is no shifting of gears,—that the driving gears are always in mesh, and that the operation of the device is both simple and very effective.

Having thus described my invention, what 45 I claim is:—

1. In a device of the character described, 50 an inclosing case, a rotatable disk journaled in the case, having a plurality of apertures arranged in circles, a divided axle, a pinion fitted to each portion of the axle, their teeth entering the apertures in the disk, a driving shaft, a pinion loosely fitted to the driving shaft, its teeth adapted to enter the apertures in the disk, and means for locking 55 said last named pinion to the driving shaft; whereby the disk may be actuated.

2. In a device of the character described, 60 an inclosing case, a rotatable disk journaled in the case, having a plurality of apertures arranged in concentric circles to receive the teeth of driving and driven pinions, a divided axle, a pinion fitted to each portion of the axle, their teeth entering one of the concentric rows of apertures in the disk, 65 a driving shaft, pinions spaced apart loosely

mounted upon the driving shaft, the teeth of the last named pinions entering respective rows of the apertures in the disk, and means for alternately locking said last named pinions to the driving shaft, whereby they 70 may actuate the disk at different speed ratios.

3. In a device of the character described, 75 an inclosing case, a rotatable disk journaled in the case, having a plurality of apertures arranged in concentric circles, a divided axle, a pinion fitted to each portion of the axle, their teeth entering one of the concentric rows of apertures in said disk, anti-friction rollers journaled in the case adapted 80 to traverse the rotatable disk to maintain the latter in operative relation to the pinions, a driving shaft, pinions loosely mounted upon the driving shaft, and having engagement with the apertures and means 85 for alternately locking said last named pinions to the driving shaft, whereby the disk may be actuated at different speed ratios.

4. In a device of the character described, 90 an inclosing case, a rotatable disk journaled in the case, having a plurality of apertures arranged in concentric circles, a divided axle, a pinion fitted to each portion of the axle, their teeth entering one of the concentric rows of apertures in the disk, a driving shaft, a driven shaft actuated from the driving shaft, pinions loosely mounted upon the driving shaft, and having engagement 95 with the apertures, means for alternately locking said pinions to the driving shaft, whereby the disk may be driven at different speeds, a pinion loosely mounted upon the driven shaft, its teeth entering one 100 row of the apertures in the disk, and means 105 whereby said last named pinion may be locked to the driven shaft to rotate the disk in a reverse direction.

5. In a device of the character described, 110 an inclosing case, a rotatable disk journaled in the case, having a plurality of concentric rows of apertures, a divided axle, a pinion fitted to each portion of the axle, their teeth entering one of the concentric rows of apertures in the disk, a driving 115 shaft, pinions loosely mounted upon the driving shaft and having engagement with the apertures, a clutch member adapted to alternately lock said pinions to the driving shaft and means for manually operating 120 said clutch member.

6. In a device of the character described, 125 an inclosing case, a rotatable disk, having a plurality of holes arranged in concentric circles, a divided axle, a pinion fitted to each portion of the axle, adapted to be actuated through said disk, a driving shaft, a driven shaft, means for operably connecting the driving shaft with the driven shaft, pinions 130 loosely carried by the driving shaft re-

spectively engaged with the circles of concentrically arranged holes in the rotatable disk for alternately operating the disk in a forward direction at different speeds, a 5 clutch for alternately locking said last named pinions to the driving shaft, a pinion carried by the driven shaft for operating the disk in a reverse direction, and a clutch

for locking said last named pinion to the driven shaft.

In testimony whereof I sign this specification in the presence of two witnesses.

PERRY J. GARRISON.
